UNITED STATES PATENT OFFICE

ULYSESS G. TODD, OF ROCHESTER, NEW YORK, ASSIGNOR TO THE PFAUDLER CO., OF ROCHESTER, NEW YORK, A CORPORATION OF NEW YORK

LIQUID-EXTRACTING MEANS

Application filed January 27, 1928. Serial No. 84,047.

The present invention relates to liquid extracting means and has for one object to provide improved apparatus for extracting the oil of vanilla from the pulp of the vanilla bean and for extracting the oils, juices or esters from other vegetable products, the apparatus being designed to thoroughly extract the entire strength from the pulp without disturbing or removing the pack or batch 10 from the container.

A further object of the invention is to provide a liquid extracting apparatus embodying improved means for holding and treating the pulp of the beans or that of other material 15 whereby to afford a more diffused spread of the percolating liquid and to reduce the time required for the extracting process, as well as to secure the maximum amount of liquid from a given quantity of pulp.

20 A further object is to provide an apparatus of the class described embodying a combined vacuum-pressure system by which a more thorough extraction of the vanilla or other liquid is afforded and by which the cost of 25 producing the extract is reduced to a minimum.

To these and other ends the invention resides in certain improvements and combinations of parts, all as will be hereinafter more 30 fully described, the novel features being pointed out in the claims at the end of the specification.

In the drawings:—

35 Figure 1 is a side elevation illustrating one embodiment of the invention;

Figure 2 is a top plan view of the same;

Figure 3 is a sectional elevation taken centrally through the tank shown in Figure 1;

40 Figure 4 is a detailed sectional elevation through the pulp holding container, and

Figure 5 is a sectional plan taken on line 5^a—5^a of Figure 4.

Figure 6 is a view of the strainer.

45 Similar reference numerals throughout the several views indicate the same parts.

Heretofore in obtaining flavoring extracts from different materials, such as vanilla beans and the like, it has been customary to place the pulp in a container and circulate 50 the liquid therethrough in the ordinary way

without the employment of means by which the process of extraction is made thorough or complete and without providing means for reducing the time required for the extracting operations, or without preventing loss 55 through evaporation. In the present invention the combined pressure-vacuum system affords an improved process by which the time of operation is greatly reduced and the quantity of the extract from a given batch 60 of pulp increased whereby a saving is effected in both ways. In the old process a great deal of time is required and several operations are necessary to obtain anything like the full strength from a given batch or quantity of 65 pulp while in the present instance only one operation is necessary which requires less time and trouble to complete, producing a higher percentage of extraction than is ordinarily obtained. 70

Referring to the drawings, 10 represents a tank or casing adapted to be supported in any desired manner, preferably by the inclined legs 11 which are suitably connected with the tank and adapted to support it at 75 the desired height. The tank is provided at its upper end with an outwardly extending flange 12 carrying a gasket 13 upon which rests the annular flange 14 of the pulp container or basket 15 shown in section in Figure 4. A cover 16 is provided for the tank which carries a gasket 17 adapted to seat upon the top of the basket flange 14 as shown in Figure 3, this arrangement serving to afford a liquid or fluid tight joint to prevent 80 the escape of the fluid from the tank. The cover or closure 16 is preferably hinged upon the tank through the medium of a pair of laterally projecting arms 18 which are pivoted at 19 to a pair of upstanding brackets 20 connected with the tank in any suitable manner. 85

A plurality of clamping devices 21 is employed, only one of which is shown, for tightly clamping the cover upon the tank, said devices being constructed in any desired manner, and preferably made so as to be quickly releasable. 95

The basket 15 is provided at its lower end with an annular reinforcing member 21 in the form of an angle iron, secured to the 100

basket preferably by riveting and having its horizontal flange extended inwardly to receive the foraminous or perforated bottom plate 22 as shown in Figure 4. This plate is 5 provided with relatively small and closely positioned perforations preferably disposed over the entire area of the plate for the escape of the liquid or menstruum percolating through the pulp 23. The foraminous bottom 10 preferably includes a wire screen 24 of relatively fine mesh which is disposed upon the bottom plate as shown in Figure 4. The pulp is preferably separated into two or more batches by a suitable screen 25 of closely 15 woven wire. An additional screen 26 is placed on top of the pulp to prevent it from being drawn upwardly by suction produced in the chamber 27, said chamber serving both as a vacuum and a pressure chamber under 20 different operating conditions which will subsequently be described. The lower or receiving chamber for the circulating liquid or menstruum is indicated at 27.

The bottom plate 22 being subjected to 25 considerable pressure is provided with reinforcing means which serves to prevent undue sagging of the plate at its center under all conditions of operation. This means preferably comprises a pair of reinforcing bars 28 and 29 disposed beneath the plate at right angles one to another, the bars being notched centrally to permit their upper faces to lie in a common plane adjacent the bottom surface of the plate 22. The bars are suitably connected at their outer ends with the inwardly extending flange of the angle iron 21 which extends entirely around the base of the basket. The bars are supported at their centers by a frame preferably comprising a pair 35 of arched supports 30 of angular construction, the outer extremities of each resting upon the screen 24 immediately over the inwardly extending flange of the angle iron 21 whereby the pressure is transferred directly 40 to the side walls of the basket. The arched supports lie adjacent each other at the center of the basket and extended over the same and downwardly through the bottom plate and through the screen thereon is a U-bolt 31 carrying at its lower end a connecting plate 32 engaging the bars 28 and 29 on the under-side thereof. The U-bolt therefore forms a direct support for the bottom plate, being in turn supported by the arched members 30, 45 as shown.

The liquid employed in the extracting process is preferably supplied to the basket when the latter is positioned within the tank and before the closure 16 is clamped in position. Water is preferably used in the extracting process and may be supplied to the container through a hose or conduit or to the circulating system of the pump.

60 A motor 33 or other means is provided for driving the circulating pump 34, one side of

which is connected with the bottom of the tank through a conduit 35 and a detachable connection 36 as shown in Figure 1. The outlet side of the pump is connected with the top of the tank through the vertical and 70 horizontal pipes 37 and 38, respectively, and a short connection 39 from which is dependably supported a rotary spray element 40 of any well known design which is adapted to be driven in the usual manner by the pressure of the liquid passing therethrough, the rotor being provided with the usual discharge ports or perforations as indicated at 75 41. The connection 39 is rendered readily detachable by turning the nut 42 which is 80 made relatively large so that it can be gripped by the hand and unscrewed without the use of a wrench or other tool. When this has been done the pipe 38 can be swung to one side to permit the cover to swing upwardly 85 upon its hinges so that the basket can be removed, emptied and replaced with a fresh batch of the pulp. However, before raising the cover the short pipe 43 with which is 90 connected the relief valve 44 must be detached from the connection 45 carried by a fixed connection 45* on the cover 16. The pipe 43 can be readily disconnected by gripping the hand nut 46 and turning it in the proper direction, after which the pipe 43 can 95 be swung to one side by turning it about the axis of the vertical suction pipe 47 which is also adapted to connect the relief valve with the tank at a point below the basket, preferably with the upper end of the suction chamber 27*. The purpose of the pipe 47 and the relief valve 44 is to afford a bypass for the liquid in the event that the basket becomes so tightly packed as to build up excessive pressure which would be sufficient to burst the basket or otherwise destroy its effectiveness, it being understood that the relief valve can be set to operate at any desired or predetermined pressure.

A suction pipe is also disposed at the opposite side of the tank as indicated at 50, the same being connected with the lower suction pipe 35 and with the top of the chamber 27* by a connection 51 and being detachable therefrom by turning the hand nut 52. The pipe 50 is provided with a regulating or cut-out valve 53 operable by means of the handle 54 and the pipe 35 is provided with a valve 55 adapted to be opened and closed by turning the hand wheel 56.

The suction pipe 50 is provided with a vacuum gauge 57 by which the extent of vacuum in the chamber 27* is indicated, while the pressure pipe 38 is provided with a pressure gauge 58 for indicating the pressure in 125 the upper chamber 27.

An electric light, not shown, is disposed within the upper chamber 27 and is supported by a fixture 59 shown in Figure 2. An observation glass 60 is carried by the closure 130

16 so that the action of the liquid may be observed within the chamber 27 whenever desired.

Below the basket on the front of the tank is an observation glass 61 and in the rear of the tank an electric light is provided, not shown, so that the percolation of the liquid downwardly into the lower chamber 27^a may be observed from time to time.

10 In order to prevent the back flow of the finer particles of pulp through the pipe 43 to the relief valve 44 a relatively fine mesh strainer 62 is dependingly carried by the fixed connection 45^a of the cover as shown in Figure 3.

15 A steam coil 63 or other desirable means for heating the accumulated liquid in the chamber 27^a at the desired time may be provided and the coil may be placed in connection with a suitable steam supply source through the inlet and outlet connections 64 and 65 in the side of the tank, or the casing 10 may be steam jacketed.

20 A filtering device 66 of any suitable type is provided in the bottom of the tank and is preferably connected with the discharge pipe 36 as shown in Figure 3, whereby all of the liquid circulated by the pump is thoroughly filtered before leaving the tank. The filtering device comprises a container having therein porous or granulated material 66^a adapted to permit the passage of air and liquid therethrough.

25 A thermometer 67 is provided adjacent the bottom of the tank for indicating the temperature of the liquid in the lower chamber 27^a, the bulb thereof being indicated at 68.

30 In the operation of the percolator the basket is packed with the finely ground pulp of the vanilla bean or other material, and is then placed in position, after which the cover is closed and clamped on and the pipes 38 and 43 connected as shown in Figure 1. The desired amount of liquid having been previously added to the pulp the valves 53 and 55 are opened and the circulating pump started. The liquid is drawn out through valve 55 by the suction of the pump and lifted under pressure through the pipes 37 and 38 and discharged into the rotary spray element 40 which revolves and sprays the circulating liquid over the top of the pulp. The liquid percolates through the pulp downwardly into the collecting chamber 27^a and completes the cycle. In these operations the pump builds up pressure on top of the pack which tends to increase circulation of the liquid through the pulp and at the same time the pump also produces a partial vacuum in the lower chamber thus tending to draw the liquid downwardly through the pulp and the perforated bottom of the basket. The pressure in the upper chamber 27 can readily be determined by observing the gauge 58 while the extent 55 of vacuum in the lower chamber will be

indicated by the vacuum gauge 57. Should the pressure become excessive in the upper chamber, the valve 44 will automatically open and the pressure will be relieved by establishing communication with the chamber below

70 since the valve is connected with the suction chamber 27^a through the pipe 47. When the pump draws a full volume of liquid the pressure tends to increase on top of the pulp and should it become excessive it can be reduced by throttling down the valve 55. Furthermore, by throttling this valve to a predetermined degree, a greater degree of suction can be produced in the upper part of the lower chamber 27^a, through the pipe 50, than is produced downwardly through the connection 36. In this way the pressure may be reduced in the chamber above the pulp by increasing the suction in the pipes 50, 47 and 43 and at the same time the increased suction below the 85 perforated bottom of the basket will have a tendency to increase the percolating action of the liquid, thus compensating for the reduction of pressure in the upper chamber 27. After extracting the vanilla or other materials to the desired extent by the cold process the heat may be applied by turning on the steam to afford the desired temperature and the process then continued.

35 In the present process of extraction the 95 liquid is completely enclosed, thereby eliminating loss of strength by evaporation. Furthermore, either the cold or hot process may be employed or both used without removing the pack or batch from the tank or without disturbing the equipment in any way, whereby a more complete or thorough extraction of the strength is afforded. The liquid may be removed from the apparatus through a suitable outlet valve not shown.

40 The basket being removable the same can be packed at any point most convenient to the supply of the pulp, after which it may be inserted in the tank at will.

45 A further advantage is that the construction is such as to effect a seal between the container flange and the tank whereby to close the compression chamber from the lower part of the tank to separate the action of the pressure on top from the vacuum underneath, thus affording a more effective process by avoiding channeling of the liquid or bypassing between the wall of the tank and the outer wall of the basket. Furthermore, the 110 rotary spray element evenly distributes the 115 liquid over the entire area of the pulp which insures circulation through all parts of the batch. By properly regulating the valves the desired pressure and vacuum can be maintained on the opposite sides of the basket, 120 and the liquid will also be maintained at the desired level, thereby increasing the effectiveness of the distribution of the liquid through the mass.

50 A further advantage is that the construc-

tion is such as to enable observation of the percolation including distribution of the liquid over the mass thereby affording accurate control of the process.

5 I claim as my invention:—

1. In apparatus of the class described, a tank, a container therein adapted to hold a batch of pulp or the like, said container having a screen in its bottom for the escape of liquid from the pulp to the tank, a rotatable spraying element in the tank above the container, means adapted both to deliver liquid under pressure to said spraying element and to tend to produce suction in the tank below the container, and means by which reduction of the pressure is automatically effected when the difference in pressure on the two sides of said container exceeds a predetermined limit.
- 10 2. In apparatus of the class described, a tank, a pulp holding container therein having a foraminous bottom, a rotary spraying element adapted to operate above the pulp container, a filtering device below the container for the liquid circulating therethrough, a pump, connections leading from the filtering device to the pump and from the latter to said rotary spraying device, and heating means for the liquid in the tank.
- 15 3. In apparatus of the class described, a tank, a pulp holding container therein including a perforated bottom, the container being connected with the tank to form a compression chamber above the pulp container from which liquid under pressure is permitted to escape only through the pulp and the perforated bottom, a vacuum chamber beneath the container, means for delivering a liquid under pressure to said compression chamber and for tending to produce suction in the vacuum chamber and means including an automatic relief valve for connecting the suction chamber with the pressure chamber under predetermined pressure in the latter.
- 20 4. In apparatus of the class described, a tank, a pulp holding container therein including a perforated bottom, the container being connected with the tank to form a compression chamber above the pulp container from which liquid under pressure is permitted to escape only through the pulp and the perforated bottom, a vacuum chamber beneath the container, means for delivering a liquid under pressure to said compression chamber and for tending to produce suction in the vacuum chamber, a relief valve and connections leading from said suction and compression chambers to said valve.
- 25 5. In apparatus of the class described, a tank, a pulp holding container therein including a perforated bottom, the container being connected with the tank to form a compression chamber above the pulp from which container liquid under pressure is permitted to escape only through the pulp and the perforated bottom, a receiving chamber for the liquid below the container, a pump, a suction pipe leading from the bottom of said receiving chamber to said pump, a connection leading from the pump to said compression chamber, a second suction pipe leading from the upper end of the receiving chamber to the first mentioned suction pipe, and a valve in each of said suction pipes whereby to vary the degree of suction applied above and below the liquid in the receiving chamber.
- 30 6. In apparatus of the class described, a tank, a pulp holding container therein including a perforated bottom, the container being connected with the tank to form a compression chamber above the pulp container from which liquid under pressure is permitted to escape only through the pulp and the perforated bottom, a receiving chamber for the liquid below the container, a pump, a suction pipe leading from the bottom of said receiving chamber to said pump, a connection leading from the pump to said compression chamber, a second suction pipe leading from the upper end of the receiving chamber to the first mentioned suction pipe, a valve in each of said suction pipes whereby to vary the degree of suction applied above and below the liquid in the receiving chamber, a pipe leading from the upper end of the receiving chamber to said compression chamber, and a relief valve interposed in said pipe.
- 35 7. In apparatus of the class described, a tank having an annular flange formed on its upper end, a pulp holding container disposed within the tank and provided with a perforated bottom and having a flange seated upon said tank flange, a removable closure for the tank resting upon said container flange and forming a sealed joint therewith whereby a compression chamber may be formed between the closure and the container, and means for delivering liquid under pressure to said compression chamber.
- 40 8. In apparatus of the class described, a tank having an annular flange formed on its upper end, a pulp holding container disposed within the tank and provided with a perforated bottom and having a flange seated upon said tank flange, a removable closure for the tank resting upon said container flange and forming a sealed joint therewith whereby a compression chamber may be formed between the closure and the container, a rotary spraying device within said compression chamber, and means for delivering liquid under pressure to said spraying device.
- 45 9. In apparatus of the class described, a container for holding a batch of pulp or the like including a perforated bottom, angular shaped arched members within the container having their middle portions disposed adjacent each other over the center of the perforated bottom and their extremities resting upon the bottom adjacent the side walls of

the container, and means extending upwardly from the bottom adapted to connect the latter with said arched members.

10. In apparatus of the class described, a container for holding a batch of pulp or the like having a perforated bottom, angular shaped arched members within the container having their middle portions disposed adjacent each other over the center of the bottom and their extremities resting upon the bottom adjacent the side walls thereof, cross bars disposed beneath the bottom and connecting means between the cross bars and the arch shaped members located adjacent the center of the container.

11. In apparatus of the class described, a container for holding a batch of pulp or the like having a perforated bottom, a frame within the container resting upon the bottom thereof adjacent its side walls and arched upwardly at the center of the container, reinforcing means for the bottom disposed therebeneath, and connecting means adjacent the center of the container between said reinforcing means and said arched frame.

12. In apparatus of the class described, a tank having a compartment arranged to hold a batch of pulp through which liquid is adapted to percolate, a pressure chamber above the pulp compartment, a chamber below the pulp compartment in the bottom of which the percolating liquid is received, a filter in the bottom of the last mentioned chamber, a pump having a pipe leading to the pressure chamber and suction pipes connected with the pump one of which leads to the filtering device and another to the upper portion of the lower chamber to tend to produce suction therein beneath the pulp compartment whereby to assist in passing the liquid through the pulp.

13. In apparatus of the class described, a closed tank, a material holding container therein separating the tank into an upper pulp chamber and a lower liquid chamber, said container having a perforated bottom, a pump, a suction pipe leading from the bottom of said liquid chamber to said pump, a second suction pipe leading from the upper end of said liquid chamber to said first mentioned suction pipe, a connection from the pump to said upper chamber and control means in each of said suction pipes whereby to vary the relative amounts of fluid drawn by the pump from above and from below the liquid level in said liquid chamber.

14. In apparatus of the class described, a closed tank, a material holding container therein separating the tank into an upper pulp chamber and a lower liquid chamber, said container having a perforated bottom, a pump, a suction pipe leading from the bottom of said liquid chamber to said pump, a second suction pipe leading from the upper end of said liquid chamber to said first

mentioned suction pipe, a connection from the pump to said upper chamber, control means in each of said suction pipes whereby to vary the relative amounts of fluid drawn by the pump from above and from below the liquid level in said liquid chamber, a conduit connecting the liquid chamber with said upper pulp chamber, and a pressure relief valve interposed in said conduit.
